US00D504874S

(12) **United States Design Patent** (10) Patent No.: **US D504,874 S**
Celaya et al. (45) Date of Patent: **** May 10, 2005**

(54) **SEMICONDUCTOR DEVICE PACKAGE**

(75) Inventors: **Phillip Celaya**, Gilbert, AZ (US);
Darrell D. Truhitte, Phoenix, AZ (US);
Michael J. Seddon, Gilbert, AZ (US)

(73) Assignee: **Semiconductor Components
Industries, LLC**, Phoenix, AZ (US)

(**) Term: **14 Years**

(21) Appl. No.: **29/211,046**

(22) Filed: **Aug. 11, 2004**

(51) LOC (7) Cl. **13-03**

(52) U.S. Cl. **D13/182**

(57) **CLAIM**

We claim the ornamental design for a semiconductor device package, as shown and described.

DESCRIPTION

FIG. 1 is a perspective view from the front left side and below the semiconductor device package showing our new design.

FIG. 2 is a top plan view thereof;

FIG. 3 is a bottom plan view thereof; and,

FIG. 4 is an elevational view from the front side thereof.

1 Claim, 3 Drawing Sheets

FIG. 1

FIG. 2

FIG. 3

FIG. 4
